United States Patent Office

Des. 187,240
Patented Feb. 16, 1960

187,240

HOLDER FOR A PUNCHABLE CARD

William H. Harkins, Vestal, and Walter Furlani and Albert W. Kapfer, Endicott, N.Y., assignors to International Business Machines Corporation, New York,
N.Y., a corporation of New York

Application January 17, 1958, Serial No. 49,290

Term of patent 14 years

(Cl. D74—1)

FIG. 1.

FIG. 2.

FIG. 3.

FIG. 4.

Fig. 1 is a top plan view of a holder for a punchable card showing our new design;

Fig. 2 is a side elevational view, the side opposite thereto being identical in appearance;

Fig. 3 is a bottom plan view; and

Fig. 4 is a sectional view thereof taken on line 4—4 of Fig. 1.

We claim:

The ornamental design for a holder for a punchable card, as shown and described.
